HAND RAIL FOR FIRE ESCAPES

Filed April 17, 1929

Witness: *Fred G. Fischer.* Inventor: *Ralph W. Downes,*
F. G. Fischer,
By *Attorney.*

UNITED STATES PATENT OFFICE

RALPH W. DOWNES, OF KANSAS CITY, MISSOURI, ASSIGNOR TO NATE W. DOWNES, OF KANSAS CITY, MISSOURI

HANDRAIL FOR FIRE ESCAPES

Application filed April 17, 1929. Serial No. 355,919.

My invention relates to hand rails for use at the entrances of tubular fire-escapes such as are installed on school and other buildings, and one object is to provide an appliance of this character which will accommodate persons of different heights and aid the advancement of persons into the tube so that there will be no delay in getting into proper position for sliding down to safety.

10 Another object is to arrange the hand rails in such manner that two small children may simultaneously enter the tube and thus materially reduce the time required for evacuating a burning building.

15 Another object is to so arrange the hand rails that they can be readily found by the blind of an asylum who are generally instructed to grope their way along the wall leading to the fire-escape.

20 Other objects will hereinafter appear and in order that the invention may be fully understood, reference will now be had to the accompanying drawing, in which:

Fig. 1 shows a front elevation of the entrance to the fire-escape, the doors being closed and the adjacent floor structure being shown in section.

Fig. 2 is a vertical section on line 2—2 of Fig. 1, with the doors in open position.

30 Fig. 3 is a horizontal section on line 3—3 of Fig. 1.

Referring in detail to the different parts, A designates the upper portion of a tubular fire escape, the entrance to which is controlled by a pair of doors B hinged to a frame C and which when opened, swing into the entrance of the fire escape. The foregoing may be of usual or any preferred construction.

Referring now more particularly to the parts constituting the present invention, 2 designates a hand rail which extends transversely across the upper portion of the doorway and is securely fastened at its ends to the door frame C by any suitable means, screws 4 being shown in the present instance. As disclosed more clearly by Fig. 1, the hand rail 2 is bent downwardly intermediate its ends as indicated at 6 so that it can be readily reached by persons of different heights, the lower portion 6 also serving to center the

person at the entrance of the tube A, thereby facilitating the proper entrance into said tube. In addition to the hand rail 2 being bent downwardly as stated, it is also bent backwardly adjacent its ends as indicated at 8, Fig. 3, so that its main portion will stand outwardly from the door frame C for a purpose which will hereinafter appear.

In addition to the transverse hand rail 2, I also provide a pair of hand rails 10 which are firmly secured at their upper ends to the hand rail 2 and extend downwardly close to the opposite sides of the door frame C. In the present instance, I have shown T-couplings 12 for uniting the hand rails 10 with the hand rail 2, although other means of securing such as welding, for instance, may be substituted. The lower portions of the hand rails 10 are curved outwardly in opposite directions and then backwardly as indicated at 16 towards the door frame C, to which they are firmly secured by suitable means such as screws 18.

All of the hand rails may be made of any suitable fire-proof material, such for instance as smooth metal tubings which are flattened at their ends as indicated at 20 and 22 to provide a flat bearing surface against the door frame C and so that said ends may be drilled or punched for the passage of the screws 4 and 18 or other fastening means employed.

With the hand rails 6 and 10 arranged as shown and described it is apparent that adults or large children may easily grasp the lower intermediate portion 6 of the hand rail 2, while smaller children may grasp the hand rails 10 and swing themselves into the entrance of the fire escape to facilitate their descent to safety. Also by having the hand rails project away from the door frame C as shown and described, they can be more readily found by the blind, who in asylums, are taught in fire drills to grope their way along the wall to the entrance of the fire-escape. The hand rails 6 and 10 also constitute a brace for each other so that they may successfully withstand all strains to which they are likely to be subjected while in use.

While I have shown a preferred embodiment of the invention, I reserve all rights to

such other forms and modifications thereof as properly fall within the spirit and scope of the invention as claimed.

Having thus described my invention, what I claim and desire to secure by Letters Patent, is:

1. In combination with a fire escape having an entrance thereto, a hand rail extending across said entrance and secured to the opposite sides of the latter, said hand rail having a depression intermediate its ends.
2. In combination with a fire escape having an entrance thereto, a hand rail extending across said entrance and which is bent backwardly near its ends and secured to the opposite sides of the entrance, said hand rail also having a depression intermediate its ends.
3. In combination with a fire escape having an entrance thereto, a hand rail extending across said entrance and secured to the opposite sides of the latter, and a downwardly extending hand rail secured to the first-mentioned hand rail and one side of the entrance.
4. In combination with a fire escape having an entrance thereto, a hand rail extending across said entrance and secured to the opposite sides of the latter, and a pair of hand rails secured at their upper ends to the first-mentioned rail and at their lower ends to opposite sides of the entrance.
5. In combination with a fire escape having an entrance thereto, a hand rail extending across said entrance and which is bent backwardly near its ends and secured to the opposite sides of the entrance, and two hand rails secured at their upper ends to the first-mentioned hand rail and which are bent backwardly at their lower portions and secured to opposite sides of the entrance.

In testimony whereof I affix my signature.

RALPH W. DOWNES.
